(57) **CLAIM**

The ornamental design for a canopy center top cap and pole combination, as shown and described.

DESCRIPTION

FIG. 1 is front elevation view of our design for a canopy center top cap and pole combination;

FIG. 2 is a rear elevation view thereof;

FIG. 3 is a left side view thereof;

FIG. 4 is a right side view thereof;

FIG. 5 is a perspective view thereof; and,

FIG. 6 is a top plan view thereof.

The broken lines are for the purpose of illustrating portions of the article that form no part of the claimed design.
